UNITED STATES PATENT OFFICE.

CHARLES H. EIMERBRINK, OF YORK, PENNSYLVANIA.

REGISTERING MECHANISM.

No. 872,916.

Specification of Letters Patent.

Patented Dec. 3, 1907.

Application filed August 25, 1906. Serial No. 332,066.

To all whom it may concern:

Be it known that CHARLES H. EIMERBRINK, a citizen of the United States, residing at York, in the county of York and State 5 of Pennsylvania, has invented certain new and useful Improvements in Registering Mechanisms, of which the following is a specification.

In sorting tobacco, from bulk, it is customary to lay the different sizes in separate piles, and finally to count the pieces in each pile.

It is the object of my invention to provide a registering device adapted particularly for use in sorting tobacco, whereby, in separating tobacco from bulk, the number of pieces in each pile may be registered, so that counting of the pieces after the tobacco has been separated is obviated.

With this object in view, the invention consists in the novel construction, combination, and arrangement of parts of a device characterized by my invention, as will be hereinafter fully described in the specification, summed up in the claims, and illustrated in the drawings, in which latter:

Figure 1 is a fragmentary front elevation of a register embodying my improvements, part of the casing being broken away to show 30 the parts behind; Fig. 2 is a side sectional elevation; Figs. 3 and 3^a are details of the escapement; and Fig. 4 is a detached view of one of the push-button keys and parts between the same and the rock-shaft bearing 35 the escapement dogs.

Referring to the drawings, 1 indicates a suitable casing, containing the working parts of my device, and which comprises two sections, one, lettered 2, containing the escapement mechanism and the chain of gearing, and the other, lettered 3, containing the bank of key-stems and connected parts.

Extending through the horizontal top plate 3^a of section 3 are the key-stems 4, 45 adapted to be depressed by the finger of the operator, through the medium of the buttons 5. Guiding sleeves 6 are provided for the upper ends of the key-stems, and are secured, as shown, in the top plate 3^a.

Secured to the inner side wall of section 3 50 is a bracket 7, one for each key-stem, which has an angled apertured portion 9, forming a bearing for a rocker-shaft 9^a, an angled apertured lug 8 in which the lower portion of stem 4 is received, and a pin 10 (for a purpose presently appearing).

Secured rigidly to the front or outer end of the rocker-shaft 9^a is a rocker-arm 11. It will be seen that the lower end of the key-stem 4 rests upon the upper surface of rocker-arm 11, whereby downward depression of said key-stem depresses the rocker-arm 11, thereby rocking or rotating the shaft 9^a. A retractile spring 14, one end thereof secured to the pin 10 and the other end thereof secured 65 to a finger 15 of the rocker-arm 11, returns the rocker-arm to normal horizontal position, coincidently, also, returning the key-stem 4 to normal position after actuation thereof.

Rigidly carried by the inner end of rocker-shaft 9^a is a crank-arm 16, to which is pivotally connected at 17 one end of a bent link or rod 18, the other end whereof is pivoted, at 19, to a rotatable disk 20, rigidly secured to which is a vertical rod or rock-shaft 21, supported towards the upper end by a bracket 22. A retractile spring 23, one end thereof secured to a pin 24 and the other end to disk 20, returns the rock-shaft to normal position, after actuation. It will be seen that the 80 springs 14 and 23 coöperate to return all the key-connected parts to normal position.

The upper end of the shaft 21 carries a pair of escapement dogs, a rigid dog 27 and a loose dog 31, the latter being weighted at 30 85 to tilt it forward along the escape wheel 29 a distance corresponding to one graduation on the dial 34, when said loose dog is not engaged by the escape wheel. As this general type of escapement is well understood, detailed description will be unnecessary. Obviously, either the loose or the rigid dog may be normally in engagement with the wheel. The latter permits the step by step movement of the chain of gears, connected with the shaft 95 of the escape wheel, and the consequent movement of the pointer 33 coöperating with the dial 34. The chain of gears is driven by the spring 35, which is wound in the usual manner, at 36. It will be noted that 100 the mechanism for operating each pointer 33 of the series is identical, except that the rocker-shafts 9^a and links 18 are graduated in length.

It will be seen that rotation of rocker-shaft 105 9^a will swing the crank-arm 16, which will exert a pull on the link 18, thereby rotating the disk 20 and the shaft 21, effecting actuation of the escapement-dogs 27 and 31, and permitting movement of the escape wheel 29. 110

The button on the top end of each key-stem may be labeled with the name of a par-

ticular grade of tobacco leaf, each button bearing the name or number of a different grade, and, as the tobacco leaves are sorted from the bulk and laid in different piles, the 5 proper key-stem is depressed for each leaf, and thus the number of leaves in each pile is registered.

Having thus fully described my invention, I claim:

- 10 1. In a registering-mechanism, and in combination with an escapement-wheel, a vertical key-stem, a horizontal rocker-shaft, a rocker-arm secured to the forward end thereof, and upon which the lower end of the key-
15 stem bears; and intermediate mechanism operatively connected to the rocker-shaft for permitting movement of the escapement-wheel upon actuation of the rocker-shaft.

2. In a registering-mechanism, and in combination with an escapement-wheel, a vertical key-stem, a horizontal rocker-shaft, a rocker-arm secured to the forward end thereof, and upon which the lower end of the key-
25 stem bears, a rotatable shaft carrying escapement-dogs engaging with the escapement-wheel, and intermediate mechanism operatively connected to the rocker-shaft and to said rotatable shaft for actuating the latter and the escapement-dogs carried thereby.

In testimony whereof I have signed my 30 name to this specification in the presence of two subscribing witnesses.

CHARLES H. EIMERBRINK.
